UNITED STATES PATENT OFFICE.

GRAHAM H. JACKSON, OF NEWARK, NEW JERSEY, ASSIGNOR TO UNIVERSAL
TOBACCO MACHINE COMPANY, A CORPORATION OF NEW YORK.

TOBACCO STEM ROLLING AND LEAF BOOKING MACHINE.

1,387,545.

Specification of Letters Patent. Patented Aug. 16, 1921.

Application filed March 25, 1919. Serial No. 284,964.

To all whom it may concern:

Be it known that I, GRAHAM H. JACKSON, a citizen of the United States, residing at Newark, county of Essex, and State of New Jersey, have invented certain new and useful Improvements in Tobacco Stem Rolling and Leaf Booking Machines, fully described and represented in the following specification and the accompanying drawings, forming a part of the same.

This invention relates to an improved machine for treating and booking tobacco leaves, by rolling or crushing the leaf stem without injury to the leaf and in such a manner that the stem may be used for the purposes of leaf tobacco, and then booking the leaves with the stems thus treated, the particular object of the invention being to provide such a machine which shall be efficient in action and at the same time simple, compact and durable, and in which all the parts are readily accessible for observation, cleaning and repair.

For a full understanding of the invention a detailed description of a combined leaf treating and booking machine embodying all the features of the invention in their preferred forms will now be given in connection with the accompanying drawings forming a part of this specification, and the features forming the invention then specifically pointed out in the claims.

In the drawings:

Figure 1 is an end elevation of the machine, from the gear side;

Fig. 2 is a front elevation looking to the right in Fig. 1, with parts broken away to show the construction;

Fig. 3 is a vertical section on the line 3—3 of Fig. 2;

Fig. 4 is a horizontal section through the stem rolling mechanism on the line 4—4 of Fig. 3;

Fig. 5 is a detail plan of the lower roll mounting, partly sectioned to show the knife pivot;

Fig. 6 is a detail vertical section on the line 6—6 of Fig. 2, and

Fig. 7 is a detail horizontal section on the line 7—7 of Fig. 3.

Referring to the drawings, A is the machine frame; B, C the upper and lower stem rolling or crushing rolls; D the swinging

frame in which these rolls and coacting parts are mounted; E the feed board over which the leaves are fed to the rolls B, C; F the booking roll, and G the booking belt, which is extended forward close to the rolls B, C, and acts to carry the leaves from these rolls, a single continuous belt being shown, although it may be divided into two or more belts.

The rolls B, C are preferably plain metal rolls, although they may be otherwise formed for special treatment of the stem, and are mounted in sliding boxes 10 spring pressed apart by intermediate springs 11, against the tension of which the upper boxes 10 are adjustable by set screws 12 so as to secure accurately the relative positions of the rolls required for crushing or flattening the stems without crushing or otherwise injuring the leaf, and hold them positively in this position during operation. This is especially necessary in connection with the tip of the leaf, as this is most liable to injury. The leaves are preferably fed butt first, as shown in Fig. 4, but may be fed tip first.

With the top roll B coacts a scraper or knife 13 to assure removal from the roll of the crushed stem and leaf, this knife 13 being carried by arm 14 pivoted on bar 15 for adjustment and locked thereon in adjusted position by set screw 1, the bar 15 being carried by arms 16 mounted to swing on roll frame D and held in working position with knife 13 pressed against roll B, by spring 17 against the tension of which the arms may be rocked to draw the bar 15 and knife 13 upward and away from the roll by handle 18. The scraper or knife 19 coacting with the lower roll to assure the removal of the stem and leaf is carried by bar 20, which also carries by arms 21 the freely rotating roll 22 around which passes the front feeding portion of belt G, bar 20 being in turn carried by bar 23 in which is mounted by arms 24 the freely rotating bearing or tension roll 25 of belt G. The belt pressure on roll 22 holds the knife 19 against the roll in the proper position and under the required tension in any position of the roll. The knife 19 is preferably supported in arms 21 by simply being set into slots in the bar, the knife and arms being provided with shoulders at the ends to hold the knife

in position longitudinally, so that the knife may readily be removed for cleaning when withdrawn from the roll.

As shown clearly in Figs. 5 and 6, in connection with the bottom knife 19, both knives 13 and 19 are mounted by horizontal central pivots 26, so that these knives with their carrier bars, and, in the case of the lower knife, with the roll 22 and portion of the belt G passing around it, rock vertically on this central pivot in such a manner as to follow the surface of the rolls B, C, with which they coact, as the position of these rolls may change by movement in the operation of the machine, thus assuring proper action of the knives in cleaning the rolls and of the front end of the belt in receiving the tobacco. The knife 13 is preferably simply slipped over the pivot stud 26 so as to be readily removed for cleaning when withdrawn from the roll.

Above the rolls 22, 25 and the portion of the belt G running over them, and supported by pivoted bar 20, is a bar 27 which may be held simply by being provided with openings through which it may be slipped onto pins 2 on bar 20, this bar 27 carrying a guide plate 28 above belt G, the portion of this guide plate next the rolls B, C being divided into fingers 3 entering between the sections of disk roll 29 mounted to rotate freely in arms on bar 27. At the rear end above roll 25 this guide plate is preferably provided with openings 4 through which the position and condition of the leaf on belt G can be observed, as the leaf passes to the booking machine. The disk roll 29, with fingers 3 coacting with belt G, assure the proper feed of the leaf as it passes from the rolls B, C to the belt. By this construction and the position of the rolls 22, 29 close to the knives 13, 19, and by making the knife 19 so as to substantially bridge the space between the roll C and the belt G, as shown particularly in Fig. 6, I am able to handle short tobacco, which is very important.

The roll frame D carrying the rolls and upper scraper, is pivoted by arms 30 and pivot 31 on frame A, so that the roll frame D with the parts carried thereby may be swung away from the booking roll and belt, permitting free access to the latter, the frame D being held in the withdrawn position by stops 32 coacting with shoulders 33 on the frame and held in operative position by stops 34 engaging the frame. The bar 23, and parts previously described as mounted thereon, is mounted to swing in the frame A on pivots 35, and is provided with handle 35' by which this bar and all the parts carried thereby may be swung back on these pivots toward the booking roll, thus providing space for the outward swinging movement of the roll frame D and parts carried thereby. In swinging back the movement is

past the dead center, so that the tension of belt G holds the bar 23 and parts thereon in the withdrawn position.

It will be seen, therefore, that by rocking the frame carrying the upper knife 13 so as to raise the latter from the roll, and tilting back the bar 23 and parts carried thereby, ready access to the inner sides of the rolls B, C, without rocking roll frame D, may be had, or the roll frame D and the parts carried thereby may be rocked forward for free access to these parts and to the booking portion of the machine.

Referring now to the booking portion of the machine, the booking belt G passes from above the rolls 22, 25 around the booking drum F, then around rolls 36, 38 mounted in parallel swinging arms 39, 39' and links 37 connecting the rolls, the arms 39 being pivoted by shaft 40 in the frame of the machine. From roll 38 the booking belt passes around roll 41 carried by arms 42 mounted by shaft 43 in the frame, and thence around fixed roll 44 to the underside of roll 22. The booking belt with its rolls 36, 38, may be thrown upward and rearward away from the surface of the drum F into the position shown in dotted lines in Fig. 3, so as to give ready access to the booked leaves thereon for removal or otherwise, the connections for this purpose being as follows: Shaft 40, carrying arms 39, links 37 and rolls 38 and 36, has rearwardly extending actuating arm 45 connected by link 46 to one arm 47 of a crank lever on pivot stud 48, the other arm 49 being connected by link 50 to an arm 51 of a crank lever mounted on pivot stud 52, the other arm forming handle 53 for operating it, so that by throwing the handle 53 forward, arm 45 is drawn down to rock shaft 40 and raise the belt and rolls 36, 38 away from the drum. The belt is held under tension while thus thrown back, by tension roll 41 spring pressed by spring 54 connected to the frame and to an arm 55 on rock shaft 43 of the roll carrying arms 42. Arm 45 carries stop 5 coacting with arm 46 on the return of the parts to operative position.

It is desirable that the belt G should be held extended transversely and in proper position, and for this purpose the opposite edges of the belt are provided with inwardly extending enlarged edges which run in grooves 6 formed in the belt rolls. It is preferable, also, that some provision be made for the enlargement of the pad of leaves opposite the roll 36 and crushing or matting of the tobacco be prevented, this being especially important in handling filler tobacco, and for this purpose the roll 36 is preferably made of end disks or heads carrying the grooves 6 and mounted to slide on the roll shaft 7, spring 8 on the shaft between the disks acting to press them apart while per-

mitting the belt to bow into the space between the disks forming roll 36 by drawing the disks toward each other against the tension of spring 8. The bunch is thus accommodated while the required pressure of the belt opposite roll 36 is secured. It will be seen that the roll 36 is positioned so that the belt keeps control of the leaf practically throughout the revolution of the drum.

10 The driving mechanism shown is as follows, but may, of course, be of any other suitable form:

The power shaft 56 drives the lower roll C directly through chain belt 57 with spring 15 pressed tension roll 58, and the two rolls B, C are geared together by two gears 59. It will be understood that belt 57 will be thrown off when frame D is tipped forward. Shaft 56 drives the booking roll F through 20 pinion 61 on the shaft 56, gear 62, intermediate 63 and gear 64 on the roll shaft.

Any suitable one revolution clutch and stop may be used for the purpose of stopping the booking roll in proper position at the end of 25 each rotation, so as to receive and book in proper position a leaf at each rotation of the roll. The machine shown is equipped, however, for booking two pads of leaves simultaneously, or a single pad, the machine taking either two leaves at each rotation of the roll or a single leaf, and for this purpose the preferred construction shown is as follows: Gear 62, through which the booking roll is driven is mounted on a sleeve 65 splined on 30 a shaft 66, and this sleeve carries also another gear 67, a spring pressed key 68 being carried by the end of shaft 66 within sleeve 65, which key projects through the sleeve and keys one or the other of gears 62, 67 to the 35 sleeve 65, by engagement with recesses 9 in the hubs of the gears, these recesses and the outer end of key 68 being rounded so as to permit the key to move with shaft 66 from one gear to the other by yielding of 40 the key against spring pressure. Sleeve 65 carries stop 100 in position to engage stop 101 on the frame, which is mounted to slide vertically so as to be withdrawn out of the path of stop 100 by link 69 actuated by 45 treadle 70, the stop and treadle being connected to swinging arm 71 which is linked to one arm of bell crank lever 72, the other arm of which is connected by link 73 to clutch lever 74, which controls clutch 75 by which 50 shaft 56 is connected to or disconnected from power pulley 76. This clutch may be of any suitable form, but is shown as that of my Patent No. 1,088,425, February 24, 1914. Downward movement of the treadle 70 thus 55 withdraws stop 101 to permit the rotation of sleeve 65 with shaft 66 and at the same time throws in clutch 75 to drive shaft 56 and parts operated thereby, and, the treadle then being released, stop 101 returns to position 60 in the path of stop 100 and acts to stop the

sleeve 65 and the operating parts of the machine against the friction of clutch 75 at the end of one revolution of the sleeve 65.

With the parts connected as shown in the drawing, that is, with gear 62 keyed to sleeve 70 65 by key 68, the booking drum F will make one full rotation during each revolution of the sleeve 65 and one leaf or pad will be booked. If two pads of leaves are to be booked on roll F by making one-half rotation of the drum F at each operation of the machine, shaft 66 will be moved longitudinally to the right in Fig. 2 by handle 77, thus releasing gear 62 from sleeve 65 and keying gear 67 to the sleeve, in which case the sleeve 80 65 with stop 100 will be rotated by gear 67 driven by gear 78 on shaft 56, and at such speed that it makes a full revolution during a half rotation of booking roll F. If a leaf be then fed to the rolls B, C over feeding board 85 E at each starting of the machine by treadle 70, two pads of leaves will be booked in proper position on booking roll F. Returning to booking a single pad on the roll F may be made simply by drawing shaft 66 to the 90 left by handle 77 into the position shown in Fig. 2, in which gear 62 is keyed to sleeve 65. Any suitable arrangement may be used for enabling the operator to stop the drum during a rotation if desired, such means being 95 well known in the art and, therefore, not illustrated.

While the invention has been described in connection with a complete machine, combining the operations of stem rolling and booking the complete leaf, and the invention relates especially to such a combined machine, it will be understood that the invention includes certain features which may be used in separate machines for stem treating or for 100 105 booking, and is thus claimed.

What is claimed is:

1. The combination with stem crushing rolls between which the tobacco leaf is fed, of a booking drum, a booking belt coacting 110 with the drum and of such width as to properly support the whole leaf, said belt being arranged at one side of the crushing rolls with no part of the belt touching the rolls, and a belt roll closely adjacent to the delivery side of said stem crushing rolls and around which said booking belt passes to receive the leaf from the crushing rolls.

2. The combination with stem crushing rolls between which the tobacco leaf is fed, 120 of a booking drum, a booking belt coacting with the drum and arranged at one side of the rolls with no part of the belt passing between the rolls, a belt roll closely adjacent to the delivery side of said stem crushing rolls and around which said booking belt passes to receive the leaf from the crushing rolls, and an upper roll coacting 125 with the feeding end of the belt in receiving the leaf from the crushing rolls.

3. The combination with stem crushing rolls between which the tobacco leaf is fed, of a booking drum, a booking belt coacting with the drum, a belt roll closely adjacent to the delivery side of said stem crushing rolls and around which said booking belt passes to receive the leaf from the crushing rolls, and a disk roll with guide fingers between the disks coacting with the feeding 10 end of the belt in receiving the leaves from the crushing rolls.

4. The combination with stem crushing rolls between which the tobacco leaf is fed, of a booking drum, a booking belt coacting with the drum, a belt roll closely adjacent to the delivery side of said stem crushing rolls and around which said booking belt passes to receive the leaf from the crushing rolls, a disk roll with guide fingers between 15 the disks coacting with the feeding end of the belt in receiving the leaves from the crushing rolls, and a guide plate extending from said disk roll over the booking belt for guiding the leaf on the belt until it 20 reaches the booking drum and provided with openings for inspection of the leaf.

5. The combination with stem crushing rolls between which the tobacco leaf is fed, of a booking drum, a booking belt coacting with the drum, a belt roll closely adjacent to the delivery side of said stem crushing rolls and around which said booking belt passes to receive the leaf from the crushing rolls, a disk roll with guide fingers between the 30 disks coacting with the feeding end of the belt in receiving the leaves from the crushing rolls, and a guide plate extending from said disk roll toward the booking drum over the booking belt for holding the leaf on the 35 belt, said disk roll, fingers, and guide being detachably mounted on the belt support for access to the upper surface of the belt.

6. The combination with stem crushing rolls between which the tobacco leaf is fed, of a booking drum, a booking belt coacting with the drum, a belt roll closely adjacent to the delivery side of said stem crushing rolls and around which said booking belt passes to receive the leaf from the crushing rolls, 45 and a scraper or knife coacting with the lower crushing roll and bridging the space between the belt and roll.

7. The combination with stem crushing rolls between which the tobacco leaf is fed, of a booking drum, a booking belt coacting with the drum, and a belt roll closely adjacent to the delivery side of said stem crushing rolls and around which said booking belt passes to receive the leaf from the 55 crushing rolls, said belt roll being mounted in a frame pivoted centrally to rock longitudinally of the stem crushing rolls.

8. The combination with stem crushing rolls between which the tobacco leaf is fed, of a booking drum, a booking belt coacting

with the drum, a belt roll closely adjacent to the delivery side of said stem crushing rolls and around which said booking belt passes to receive the leaf from the crushing rolls, said belt roll being mounted in a frame 70 pivoted centrally to rock longitudinally of the stem crushing rolls, and a scraper or knife coacting with the lower crushing roll and mounted on said frame to rock with the belt roll. 75

9. The combination with stem crushing rolls between which the tobacco leaf is fed, a belt roll closely adjacent to the delivery side of said stem crushing rolls and around which said booking belt passes to receive 80 the leaf from the crushing rolls, said belt roll being mounted in a frame pivoted centrally to rock longitudinally of the stem crushing rolls, a scraper or knife coacting with the lower crushing roll and mounted 85 on said frame to rock with the belt roll, and a scraper or knife coacting with the upper stem crushing roll and pivoted centrally to rock longitudinally of the stem crushing roll. 90

10. The combination with stem crushing rolls between which the tobacco leaf is fed, of a booking drum, a booking belt coacting with the drum, and a belt roll closely adjacent to the delivery side of said stem crushing rolls and around which said booking belt passes to receive the leaf from the crushing rolls, said belt roll being mounted on a support movable toward and away 95 from the crushing rolls for access to the latter. 100

11. The combination with stem crushing rolls between which the tobacco leaf is fed, of a booking drum, a booking belt coacting with the drum, a belt roll closely adjacent to the delivery side of said stem crushing rolls and around which said booking belt passes to receive the leaf from the crushing rolls, and a scraper or knife coacting with the lower roll and carried by the belt roll 105 support, said support being mounted to swing vertically, whereby the belt tension holds the scraper or knife against the crushing roll. 110

12. The combination with stem crushing rolls between which the leaf is fed and a booking drum and booking belt adjacent the rolls, of a frame in which the rolls are carried and mounted to have a wide movement toward and away from the drum and belt 115 120 so as to leave a clear space between the rolls and drum and belt when moved away from the latter to provide easy access to these parts.

13. The combination with stem crushing 125 rolls between which the leaf is fed, of a booking drum, a booking belt coacting with the drum, a belt roll closely adjacent to the delivery line of said stem crushing rolls and around which said booking belt passes to 130

receive the leaf from the rolls, said belt roll being carried by a support pivoted to swing away from the lower crushing roll, and a frame carrying the crushing rolls and mounted to swing away from the booking drum and belt when the belt support is swung away from the crushing roll.

14. In a tobacco leaf treating machine, two coacting stem crushing rolls of uniform diameter and surface hardness throughout mounted in bearings for relative adjustment, springs for pressing said rolls apart, and means for positively adjusting said rolls toward each other and holding them in fixed adjusted position against the tension of said springs in position for rolling the stem without injury to the leaf.

15. In a tobacco leaf treating machine, the combination with two stem crushing rolls of uniform diameter and surface hardness throughout and mounted for relative adjustment, of means for positively adjusting said rolls and holding them in fixed adjusted position for rolling the stem without injury to the leaf.

16. The combination with tobacco feeding rolls, of a booking belt, a belt roll closely adjacent to the delivery side of the rolls, and a scraper or knife coacting with the lower roll and bridging the space between the feeding and belt rolls.

17. The combination with tobacco feeding rolls, of a booking belt, a belt roll closely adjacent to the delivery side of the rolls, and a scraper or knife coacting with the lower roll and bridging the space between the feeding and belt roll, said belt roll and knife being pivoted to rock longitudinally of the roll.

18. The combination with a tobacco feeding roll, of a scraper or knife coacting with said roll and pivoted to rock longitudinally of the roll.

19. The combination with tobacco stem crushing rolls, of scrapers or knives coacting with said rolls and pivoted to rock longitudinally of the rolls.

20. The combination with a tobacco booking drum, of a booking belt, and a belt support formed of heads supporting the opposite side portions of the belt with an intermediate portion unsupported, whereby excessive pressure on the pad between said belt and drum is prevented.

21. In a tobacco booking machine, a booking belt in combination with a belt support formed with end heads having relative endwise movement and spring-pressed apart,

whereby the pad engaging portion of the belt may yield by drawing the disk together 60 against the spring pressure.

22. The combination with the belt G, of roll shaft 7, disks 36 movable endwise on said shaft, said belt having an edge connection to the heads, and spring 8 holding the 65 disks apart.

23. The combination with a tobacco booking drum, of driving means for rotating said drum at a constant speed, an automatic stop, and change driving mechanism for rotating 70 said stop at different rates of speed relatively to the drum, whereby the stop may be actuated to stop the drum after movements of different extent.

24. The combination with a tobacco booking drum, of a power shaft and gearing by which said drum is driven, an automatic stop rotating during the rotation of the drum for stopping the latter at the end of a leaf booking movement, change gearing for 80 driving said stop from the power shaft at different rates of speed relatively to the booking drum, and means for connecting said stop to the gearing for varying the speed of the stop without changing the speed 85 of the drum.

25. The combination with rolls B, C, of frame D carrying the rolls and pivoted to swing into position for access to the rolls, scraper or knife 13 coacting with the upper 90 roll, and a carrier for said scraper mounted on said frame D and movable thereon to bring said scraper into position for inspection and cleaning without moving frame D.

26. The combination with rolls B, C, of 95 booking belt G, belt roll 22 close to the delivery side of the rolls, scraper or knife 19 coacting with roll C over which the leaf passes to the belt, disk roll 29 above the belt roll, and a guide above the belt having fingers 3 between the disks, said disk roll and guide being detachable for access to the belt.

27. The combination with rolls B, C, of booking belt G, belt roll 22 closely adjacent to the delivery side of the rolls, a scraper or 105 knife 19 coacting with roll C and over which the leaf passes to the belt, and a support carrying the belt roll and knife and mounted to swing toward and from the rolls.

In testimony whereof, I have hereunto set 110 my hand.

GRAHAM H. JACKSON.
